by Morris F. Holmes Inventor:

orvis E. Holmes.

Art'y.

UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed May 1, 1922. Serial No. 557,659.

My invention relates to mining machines. It has for its object to provide an improved truck driving mechanism for such a machine, and more especially to provide an improved construction whereby the truck driving member, which in certain types of machines is disposed just above and in rear of the cutter chain passage and therefore during cutting constantly working in an atmosphere laden with dust and cuttings, may be lubricated effectively and may be maintained properly lubricated.

In the accompanying drawings, I have shown for purposes of illustration one embodiment which my invention may assume in practice.

In these drawings,—

Fig. 1 is a side elevation partially in section of a mining machine equipped with my improvement.

Fig. 2 is an enlarged vertical sectional view of the truck driving member and its lubricating connections.

In this illustrative construction I have shown a mining machine 1 of a standard motor propelled type slidable on a bottom plate or shoe 2 on the mine bottom and movable relative to flexible feeding means, herein in the form of a chain 3, through the operation of the feed operating member 4 driven from the mining machine motor (not shown) through suitable gearing including a gear 5 rotatable with the feed operating member 4; the mining machine, as in a usual construction, also carrying a cutter bar 6 projecting from its front end and in turn carrying a cutter chain 7, likewise driven by the motor, which extends beneath the frame and discharges the cuttings through the rear end of the frame and beneath a truck driving member 8, in turn driven by suitable motor driven gearing including a gear 9.

In my improved construction, the feed operating member 4 and gear 5 rotate together on an upstanding stud 10, suitably supported at its opposite ends on the rear of the machine frame, a sleeve herein being provided on the member 4 and carrying the gear 5. This stud is herein suitably fixed to the rear end of the frame, as by a key 11, and provided with an axially extending aperture 12 adapted to be filled with oil through a reduced aperture 13 in a plug 14, the plug 14 herein also acting to hold a part of the controlling mechanism 15 in position

on a removable frame section 16 in which the reduced upper end 17 of the stud is carried. As shown, the axial aperture 12 is also provided with a lateral opening 18 leading to the inner periphery of the sleeve on the feed operating member 4, so that when lubricant is supplied to the bore 12, it may lubricate the bearings for the gear 5 and feed operating member 4. Further, it will be noted that the lower end of the stud 10 is also of reduced section as at 19 and seated in the frame and that fixed to this reduced portion as by a key 20 is a stationary member 21 having a lateral port 22 communicating with the bore 12 and adapted to distribute lubricant from the bore to the outer periphery of the stationary member 21 and a cooperating longitudinally disposed or vertical groove 23. As shown, a flanged bearing sleeve 24 having a lateral groove 25 in the under surface of its flange is disposed outside this member 21 and beneath the lower surface of an outer depending flange 26 on the gear 8, while the end surface of the member 21 is recessed as at 27 to receive a hub 28 on a holding member 29 which is in turn threaded on an extension 30 of the portion 19 and held in position by a suitable cotter pin connection 31. As shown, the member 29 is also provided with an upstanding flange 32 received in a larger annular groove 33 in the gear 8 spaced by a suitable clearance from the outer periphery of the flange 26 on that gear.

In the operation of my improved construction, it will be evident that when lubricant is supplied through the passage 13 into the bore 12, it will flow out through the lateral passage 18 to the bearings for the gear 5 and feed operating member 4, while other lubricant will pass down the bore 12 and out through the lateral passage 22 to the vertically disposed groove 23 in the member 21 and groove 25 in the flanged sleeve 24, thereby lubricating the bearing sleeve 24 as the gear 8 is rotated relative to the stationary members 21 and 29, while it will be noted that the flange 32 on the member 29 effectually prevents the lubricant from escaping to the ground and instead maintains a level of lubricant closely adjacent the top of the flange 32. Thus it will be observed that as a result of my improved construction, it is possible to maintain the bearings for the truck driving gear 110

in proper condition and properly lubricated during machine operation despite the fact that it is constantly operated in a dust laden atmosphere, my improved construction not only providing a liquid seal therefor through maintaining a certain level of lubricant within the flange 32, but also, through the fit of the sleeve flange upon the bottom of the flanged bearing sleeve, further preventing the entry of any large amount of dirt or the like to the bearings. Attention is also directed to the fact that it is possible whenever desired, by simply removing the cotter pin 31 and unscrewing the member 29, to remove the bearing sleeve and gear or to remove the stud when this, for any reason, is desirable, the removable gear cover 16 permitting access to the parts beneath the same whenever desired.

20 While I have in this application specifically described one form which my invention may assume in practice, it will be understood that this form of the same is shown for purposes of illustration and that 25 the invention may be modified and embodied in other forms without departing from its spirit or the scope of the appended claims.

What I claim as new and desire to secure by Letters Patent is:

- 30 1. The combination with a mining machine presenting a cuttings passage and a truck driving gear disposed adjacent the same, of an axially bored member disposed coaxially with said gear, a member on said member having a passage communicating with said bore and disposed coaxially therewith inside said gear, and a member holding said gear in position.
- 40 2. The combination with a mining machine presenting a cuttings passage and a truck driving gear disposed adjacent the same, of an axially bored member disposed coaxially with said gear, a member on said member having a passage communicating with said bore and disposed coaxially therewith inside said gear, a bearing sleeve between said last mentioned member and said gear, and a member holding said gear in position.
- 50 3. The combination with a mining machine presenting a cuttings passage and a flanged truck driving gear disposed adjacent the same, of an axially bored member disposed coaxially with said gear, a member on said member having a passage communicating with said bore and disposed coaxially therewith inside said gear, and a member holding said gear in position having a flange 60 cooperating with the flange on said gear.
4. The combination with a mining machine presenting a cuttings passage and a flanged truck driving gear disposed adjacent the same, of an axially bored member disposed coaxially with said gear, a member

on said member having a passage communicating with said bore and disposed coaxially therewith inside said gear, and a member holding said gear in position having a flange disposed externally of the flange on said gear.

5. The combination with a mining machine presenting a cuttings passage and a truck driving gear disposed adjacent the same and having an annular recess in its under surface, of an axially bored laterally ported stud disposed coaxially with said gear, a laterally ported member fixed to said stud and disposed coaxially therewith inside said gear, and a member fixed to said stud 75 and holding said gear in position, said member having an upstanding flange disposed within the annular recess in said gear.

6. The combination with a mining machine presenting a cuttings passage and an annularly recessed truck driving gear disposed adjacent the same, of an axially bored laterally ported stud disposed coaxially with said gear, a laterally ported member fixed to said stud and disposed coaxially therewith 85 inside said gear, a bearing sleeve between said member and said gear, and a member fixed to said stud and holding said gear in position, said member having an upstanding flange disposed within the annular recess in 90 said gear, and said sleeve having an annular flange disposed between one of the flanges on said gear and said last mentioned member.

7. The combination with a mining machine having a cuttings passage and an annularly recessed truck driving gear disposed adjacent the same, of an axially bored laterally ported stud, a laterally ported member fixed to said stud, a flanged bearing sleeve surrounding said member and having a flange underlying the hub of said gear, and a retaining member fixed to said stud and having a flange surrounding the hub of said gear and cooperating therewith to present an oil seal carrying means.

8. The combination with a mining machine having a cuttings passage and an annularly recessed truck driving gear disposed adjacent the same, of an axially bored laterally ported stud, a laterally ported member fixed to said stud, a flanged bearing sleeve surrounding said member and having a flange underlying the hub of said gear, and a retaining member fixed to said stud and having a flange surrounding the hub of said gear, said member having a recess in one end thereof and said retaining member having a portion extending into said recess.

9. The combination with a mining machine having a cuttings passage and an annularly recessed truck driving gear disposed adjacent the same, of an axially bored laterally ported stud, a laterally ported member fixed to said stud, a flanged bearing sleeve surrounding said member and having 125

a flange underlying the hub of said gear, and a retaining member fixed to said stud and having a flange surrounding the hub of said gear, said laterally ported member having a longitudinally extending groove in its periphery communicating with its port and a recess in one of its ends in which the hub of said retaining member is seated and said stud having a threaded extension to which 10 the hub of said retaining member is threaded.

10. In a mining machine, feed operating and truck, driving mechanism including coaxial gears, an axially bored stud disposed axially of said gears and relative to which 15 the same are rotatable, said stud having lateral apertures leading to the bearing surfaces of said gears, and means for maintaining a lubricant seal between the bearings of said truck driving gear and the atmosphere 20 having communication with the axial bore in said stud.

11. In a mining machine, feed operating and truck driving mechanism including coaxial gears, an axially bored stud disposed 25 axially of said gears and relative to which the same are rotatable, said stud having lateral apertures leading to the bearing surfaces of said gears, and means for maintaining a lubricant seal between the bearings of 30 said truck driving gear and the atmosphere, said means having provision for preventing

the entry of foreign matter to the bearings of said gear.

12. In a mining machine, feed operating and truck driving mechanism including coaxial gears, an axially bored stud disposed axially of said gears and relative to which the same are rotatable, said stud having lateral apertures leading to the bearing surfaces of said gears, and means for maintaining lubricant in said bore and a lubricant seal between the bearings of said truck driving gear and the atmosphere, said means including a flange on said gear, a ported member between said gear and said stud, and a 40 retaining member having a flange cooperating with the flange on said gear. 45

13. The combination with a mining machine presenting a cuttings passage and a truck driving gear journaled adjacent the same, of means for retaining said gear in position on said machine presenting an oil seal for the bearings of the latter including a vertical shaft having passage means therein, a communicating laterally ported member secured thereto, a bearing disposed between said gear and said laterally ported member, and a flanged member enclosing said bearing and carried on said shaft. 50 55

In testimony whereof I affix my signature.

MORRIS P. HOLMES.
